UNITED STATES PATENT OFFICE.

JAMES PRANGLEY, OF LANCASTER, PENNSYLVANIA.

TOBACCO-BOOKING MACHINE.

SPECIFICATION forming part of Letters Patent No. 366,251, dated July 12, 1887.

Application filed March 14, 1887. Serial No. 230,868. (No model.)

To all whom it may concern:

Be it known that I, JAMES PRANGLEY, a citizen of the United States, residing at Lancaster, in the county of Lancaster and State of Pennsylvania, have invented certain new and useful Improvements in Tobacco-Booking Machines; and I do hereby declare the following to be a full, clear, and exact description of the invention, such as will enable others skilled in the art to which it appertains to make and use the same.

This invention relates to "tobacco-booking machines," so called, whereby the action of the operator in laying successive leaves of tobacco on the pile is caused to register the number of said leaves.

The object of the present invention is to make this registration easy and certain, and to provide for holding at will tobacco-leaves of greater or less length.

The said invention, therefore, consists partly of a slatted yielding table on which the tobacco-leaves are supported, in combination with springs which force said table upward and outward, and clamps which hold said leaves in position on said table, keeping the latter in the shape of an arch, substantially as herein-after set forth.

The said invention consists, also, in the combination of registering devices and a pawl or toothed arm, whereby they are actuated, with a flexible top or table for supporting the tobacco-leaves, and relatively-fixed clamps above said table, said pawl or arm moving with said table or top when the latter is depressed.

The said invention also consists in a flexible spring-actuated table or top for supporting and holding the tobacco-leaves, the relatively-fixed clamping-blocks, against which said leaves are forced by said top or table, and the means for adjusting said clamps, substantially as hereinafter set forth.

In the accompanying drawings, Figure 1 represents a front elevation of my tobacco-booker, showing clamps of the roller-form, flat springs, and the slotted adjusting-plate. Fig. 2 shows a detail view in perspective, taken from below, of the slatted table. Fig. 3 shows in front elevation a modification similar to Fig. 1, but having spiral springs. Fig. 4 is a detail perspective view of another form of the

clamping-blocks. Fig. 5 represents a rear view in elevation of the upper part of the machine. Fig. 6 represents a detail view of a modified form of the plate for supporting and adjusting the clamps, it having a series of holes instead of slots; and Fig. 7 represents a detail edge view of the dial-plate.

A designates the base of the machine, and B the supporting frame or standard raised thereon. A slat, C, is attached at its rear end rigidly to said standard or frame, and extends horizontally forward from the top of the latter, forming the crown-piece of an arched table, D. The remainder of said table is made up of slats d, which lie side by side and are attached to flat springs E, these springs being fastened at the middle to the under side of the fixed slat C. A cover, F, of tough flexible fabric, is also attached at the middle to said slat C, but on the upper side of the latter, and hides said slats and the intervals between them. These intervals are, however, very slight, but would be an inconvenience in booking the tobacco if left uncovered. Of course I do not confine myself to the particular form of spring above described. For example, spiral springs E, as shown in Fig. 3, may be employed, flexible strips e being used to connect the slats one to another.

G designates a plate attached to the upper part of the standard or frame B and extending horizontally on each side thereof. Near each end it has a slot, g, extending obliquely outward and downward with a slight curvature. This slot receives a screw-threaded rod, h, extending from the rear end of each clamp H. A thumb-nut, I, turning on the rearwardly-extending end of said screw-threaded rod, holds it and said clamp at any position of adjustment which the slot g in said plate will allow it to take. As the two ends of the plate G are alike, and the adjusting devices h I, corresponding thereto, are alike also, the adjustment of said clamps toward or from each other may easily be effected. This adjustment allows the booker to conform to leaves of greater or less length. The highest parts of the slots g are below the slat C, so that the clamps H, being held below the top of the arch of the table D, compel said table to retain the form of an arch in spite of the upward action of the springs E.

This arched form of the table is exceedingly convenient in the operation of booking. Sometimes I make use of a different form of clamp, as shown in Fig. 4. This is a six-sided clamp 5 block, marked H', broader than thick in the figure, though obviously modifiable in dimension and shape. Sometimes, as shown in Fig. 6, I provide the plate G at each end with a series of holes, g', instead of the slot g. 10 The screw-threaded rod h of each clamp is simply moved from one of these slots to another, instead of being slipped along the slot. Of course the nut I must first be removed, it being replaced after the clamp reaches its new 15 position. To the under side of one of the slats d, on the right of the upper slat, C, a lug, d', is attached rigidly. A long pawl or arm, J, is pivoted at its upper end to said lug, the lower end of said pawl or arm bearing a tooth, j, 20 which engages with the teeth of a ratchet-wheel, K, journaled on a stud, k, which extends forward from a tablet, L, fast on the front of the upper part of frame or standard B. This pawl turns said ratchet-wheel with a 25 step-by-step motion whenever the right-hand part of flexible table B is depressed. A retaining-dog, m, is pivoted to said tablet and forced into engagement with said ratchet-wheel by a spring, n. M designates a pinion 30 on the front of said ratchet-wheel, and, of course, turning with it. This pinion engages with a gear-wheel, N, turning on another stud that extends forward from said tablet. A dial, O, on the front of said wheel N, indicates 35 the number of leaves on the table by the figures which said dial successively presents up- permost. A lug, p, on the back of said dial-wheel N, strikes the tail q of a hammer, P, at- tached to said tablet, and causes said hammer 40 to strike a bell, Q, at each complete revolu- tion of the dial. The operator simply draws the leaves one after another under the clamps

and over the flexible table. Each leaf de- 45 presses the sides of the table a little more, and each depression of the right-hand side of said table causes the registering or indicating action above stated. Of course the inflexibility of the crown-slat C does not affect the general flexibility of the table nor its availability for the purposes stated. 50

Having thus described my invention, what I claim as new, and desire to secure by Letters Patent, is—

1. A flexible table and a pawl or toothed arm attached thereto, in combination with 55 clamps arranged above said table and holding it in arched form, registering devices operated by said pawl, and springs operating on said table, substantially as set forth.

2. A flexible table, clamps arranged above 60 the same, and an arm interposed between said table and the registering mechanism, in com- bination with springs for forcing said table upward toward said clamps, and registering mechanism operated by depressing said table 65 to admit the tobacco, substantially as set forth.

3. The combination of a flexible table, and 70 springs for forcing the ends of said table up- ward, with clamps arranged above said table and adjustable toward and from each other to conform to the length of the leaves, substan- tially as set forth.

4. A fixed plate, G, having slots g, in com- bination with the clamps having screw-thread- 75 ed rods and nuts for adjusting them, as de- scribed, the flexible table below said clamps, and the springs which force the said table to- ward said clamps, substantially as set forth.

In testimony whereof I affix my signature in presence of two witnesses.

JAMES PRANGLEY.
